UNITED STATES PATENT OFFICE.

HENRY C. EGERTON, OF PASSAIC, NEW JERSEY, ASSIGNOR TO WESTERN ELECTRIC COMPANY, OF NEW YORK, N. Y., A CORPORATION OF ILLINOIS.

TELEPHONE-TRANSMITTER.

1,073,667.

Specification of Letters Patent. Patented Sept. 23, 1913.

Application filed October 5, 1912, Serial No. 724,056. Renewed May 24, 1913. Serial No. 769,765.

To all whom it may concern:

Be it known that I, HENRY C. EGERTON, a citizen of the United States, residing at Passaic, in the county of Passaic and State 5 of New Jersey, have invented a certain new and useful Improvement in Telephone-Transmitters, of which the following is a full, clear, concise, and exact description.

This invention relates to telephone transmitting apparatus and has for its object to 10 provide a transmitter of few and simple parts which will be efficient in its operation and easily assembled.

In accordance with one of the features of 15 this invention, the movable electrode is mounted directly upon the transmitter diaphragm and in the assembly of the device is inclosed by means of a containing chamber formed in a metal section of the structure.

20 Another feature of this invention relates to the means provided for sealing the chamber without appreciably reducing the heat radiation, and consists in the provision of a thin washer of comparatively resilient insulating material secured directly to the diaphragm against which the edge of the containing cup bears. For this purpose a thin washer of hard felt is found to be satisfactory inasmuch as it permits sufficient movement of the diaphragm and will not pack or shrink to such an extent as to permit the comminuted material to escape from the chamber.

25 In the drawings in which this invention is 35 illustrated in connection with a push and pull type of transmitter comprising two fixed and two movable electrodes, Figure 1 is a sectional view of a transmitter embodying this invention; and Fig. 2 is a detail view of the principal parts of the transmitter.

30 As shown in the drawings, 5 designates the usual transmitter mouthpiece having screw-threaded engagement with a metal plate 6 which is provided at its center with a chamber or recessed portion 7 and a web portion 8 having a plurality of openings 9-9 therethrough leading into the chamber 7. Formed upon this web portion 8 is a lug 10, the outer end of which is of conical form and projects into the mouthpiece 5 to deflect the voice current through the openings 9-9.

The inner end of the lug 10 is recessed to form a chamber 11. Mounted in one end of this chamber is a screw-threaded stud 13 to 55 which is secured an electrode 14. Secured to the back face of the metal plate 6 is a second metal plate 18 having a recessed or chamber portion 19 at its center, a web portion 20 and a lug 21 with an opening 22 therethrough in one end of which is mounted 60 a metal stud 23 carrying an electrode 24. The portion of the web surrounding the lug 21 is provided with openings 25-25 for the passage of air from the chamber or recessed 65 portion 19. Mounted between the plates 6 and 18 is a vibrating diaphragm 30 which is insulated from said plate by means of a rubber gasket or ring 31. The plates 6 and 18 are secured together by means of 70 screws 32-32 extending through the plate 18 and engaging the plate 6. These screws pass through insulating bushings 33-34 in the plate 18 and an insulating washer 35 is interposed between these plates near their 75 outer margins. A metal spacing ring 36 is also interposed between these plates to maintain their relation with each other and with the diaphragm 30.

75 Mounted upon opposite sides of the diaphragm 30 on the central portion thereof are two electrodes 40 and 41. These electrodes are secured to studs 42 and 43 one of which has an interior screw-threaded portion 47 passing through the diaphragm 30 to 80 receive an exteriorly screw-threaded portion 48 upon the other of said studs. Spacing washers 49 and 50 are interposed between the back faces of the studs carrying the electrodes and serve also as an electrical connection between said studs and said diaphragm. The electrodes 35 and 36 extend into the chamber portions of the metal studs 10 and 21 respectively. Secured to the diaphragm 30 one on each side thereof are felt 85 rings 51 and 52 against which the inner ends of the studs 10 and 21 bear. These felt washers extend beyond the margins of the electrodes 40 and 41 and seal the openings of the chambers 11 and 22 which are partially filled with comminuted material 55.

90 As shown, stud 23 carrying the electrode 24 is mounted in a plate 59 which is adapted to be secured to the plate 18 by means of 100

screws 60—60, with said electrode in the chamber 22.

In assembling this device the chamber 11 will first be supplied with comminuted material, then the diaphragm bearing movable electrodes and the felt washers will be placed in position and the metal plates 6 and 18 secured together. Then by supplying the comminuted material to the chamber 22 and securing plate 59 thereto with the electrode in place the instrument will be ready for operation.

Secured at one end to the diaphragm 30 and at its other end to the metal plate 18 is a bowed metal spring 67 constituting a damping and circuit-connecting spring.

The structure as above described may be mounted in an ordinary transmitter bell 65 which may be secured to a desk stand or wall set in the well known manner.

The advantages of the structure above described are the elimination of mica or auxiliary diaphragms for closing the granule containing chambers. The radiation qualities of the device are not affected inasmuch as the electrodes and the contained comminuted material are so related to the metal walls of the containing cups that the heat generated in said electrodes and comminuted material will find a ready path through said walls unaffected by the felt washers. Another advantage obtained in this structure by the use of the hard felt is that after the instrument has been used a short time the felt mats down slightly, where it touches the edge of the button chamber but not sufficient to permit the escape of the comminuted material from the chamber. This will improve the transmission due to the greater freedom with which the diaphragm vibrates. While this invention is shown and described in connection with a push and pull type of transmitter in which there are employed two movable and two fixed electrodes, it will be readily apparent to those skilled in the art that the invention is not limited to this form of transmitter as it is also applicable to a single button type of transmitter for use with the ordinary telephone currents. Such a structure would result from the omission of the front electrode chamber and associated parts and all of the advantages of the invention would be embodied in such modified structure.

I claim—

1. In a telephone transmitter, a diaphragm, frame plates between which said diaphragm is supported, a granule containing cup carried by each of said frame plates, electrodes supported by said diaphragm in said cups, and means carried by said diaphragm for sealing said cups.

2. In a telephone transmitter, a diaphragm, frame plates between which said diaphragm is supported, a granule contain-

ing cup formed integrally with each of said frame plates, electrodes supported by said diaphragm in said cups and means carried by said diaphragm for sealing said cups.

3. In a telephone transmitter, a diaphragm, frame plates between which said diaphragm is supported, a granule containing cup carried by each of said plates, electrodes mounted upon opposite sides of said diaphragm and located in said cups, and resilient insulating washers mounted upon opposite sides of said diaphragm against which the adjacent ends of said cups bear.

4. In a telephone transmitter, a diaphragm, frame plates between which said diaphragm is supported, a granule containing cup formed integrally with each of said plates, electrodes mounted upon opposite sides of said diaphragm and hard felt washers secured to the opposite faces of said diaphragm against which the adjacent ends of said cups bear.

5. In a telephone transmitter, a diaphragm, frame plates between which said diaphragm is supported, movable electrodes mounted upon opposite sides of said diaphragm, granule containing chambers formed integrally with said frame plates and inclosing said movable electrodes, and a fixed electrode removably secured in one of said granule containing cups.

6. In a telephone transmitter, a diaphragm, front and back frame plates between which said diaphragm is supported, movable electrodes carried by said diaphragm, a lug formed integrally with said front plate, said lug having a conical projection on one end and being provided at its opposite end with a chambered portion surrounding one of said movable electrodes, a stationary electrode mounted in said chamber, a lug formed upon said back plate and having an opening therethrough, one end of which surrounds a movable electrode carried by said diaphragm, a stationary electrode for closing the rear end of said opening and a detachable plate carrying said last named stationary electrode, said detachable plate being secured to said back mounting plate.

7. In a telephone transmitter, a diaphragm, frame plates for supporting said diaphragm, a granule containing cup carried by one of said frame plates, an electrode supported by said diaphragm in said cup, and means carried by said diaphragm for sealing said cup.

8. In a telephone transmitter, a diaphragm, frame plates between which said diaphragm is supported, a granule containing cup formed integrally with one of said frame plates, an electrode supported by said diaphragm in said cup, and means carried by said diaphragm for sealing said cup.

9. In a telephone transmitter, a diaphragm, frame plates between which said

diaphragm is supported, a granule containing-cup carried by one of said plates, an electrode mounted upon said diaphragm and located in said cup, and a resilient insulating washer mounted upon said diaphragm against which the adjacent end of the cup bears.

In witness whereof, I hereunto subscribe my name this third day of October A. D., 1912.

HENRY C. EGERTON.
